HOSE

William H. Myerly, 1230 River Vista Drive,
Des Moines, Iowa 50315

Filed Feb. 8, 1968, Ser. No. 10,498

Term of patent 14 years

Int. Cl. D23—01

U.S. Cl. D23—44

FIGURE 1 is a side elevational view of the hose showing my new design;

FIGURE 2 is an enlarged fragmentary perspective view thereof;

FIGURE 3 is another enlarged fragmentary perspective view thereof;

FIGURE 4 is an enlarged side elevational view thereof;

FIGURE 5 is an enlarged left end elevational view thereof; and

FIGURE 6 is an enlarged right end elevational view thereof.

I claim:

The ornamental design for a hose, substantially as shown.
